DESIGN FOR A MAGNIFIER

Edward E. Van Dyke, Sherman Oaks, Calif.

Application December 10, 1945, Serial No. 124,589

Term of patent 14 years

(Cl. D57—1)

To all whom it may concern:

Be it known that I, Edward E. Van Dyke, a citizen of the United States and a resident of Sherman Oaks, in the county of Los Angeles and State of California, have invented a new, original, and ornamental Design for a Magnifier, of which the following is a specification, reference being had to the accompanying drawing, forming a part thereof.

Fig. 1 is a front perspective view of a magnifier showing my new design;

Fig. 2 is a side elevational view;
Fig. 3 is an end elevational view;
Fig. 4 is a bottom plan view; and
Fig. 5 is a top plan view thereof.

I claim:

The ornamental design for a magnifier, substantially as shown.

EDWARD E. VAN DYKE.
